APPARATUS FOR CONDITIONING AIR

Jesse A. Guyer, Mount Vernon, Ill., assignor to
 J. P. Devine Manufacturing Co., Inc., Mount
 Vernon, Ill., a corporation of Illinois

Application January 16, 1936, Serial No. 59,336

7 Claims. (Cl. 62—91.5)

This invention relates to apparatus for conditioning air, and with regard to certain more specific features, to such apparatus using a solid refrigerant, such as carbon dioxide ("dry ice"), as a refrigerating medium.

Among the several objects of the invention may be noted the provision of apparatus for conditioning air in which a solid refrigerant, such as carbon dioxide is used as a refrigerating medium, and in which the full heat absorbing capacity of the solid carbon dioxide is utilized in an economical manner; the provision of apparatus of the class described which is particularly adapted for the conditioning of air in moving vehicles, buildings, and the like; the provision of apparatus of the class described which requires no secondary refrigerating medium; the provision of apparatus for conditioning air which is so constituted as to achieve a substantially constant and controllable cooling effect over a substantial length of time; and the provision of apparatus of the class described which is economical to carry out and construct. Other objects will be in part obvious and in part pointed out hereinafter.

The invention accordingly comprises the elements and combinations of elements, features of construction, and arrangements of parts, which will be exemplified in the structures hereinafter described, and the scope of the application of which will be indicated in the following claims.

In the accompanying drawing, in which are illustrated several of various possible embodiments of the invention,

Fig. 1 is a diagrammatic layout of an air conditioning system utilizing the present invention;

Fig. 2 is a diagrammatic cross section of a refrigerating chamber;

Fig. 3 is a diagrammatic longitudinal section of the chamber shown in Fig. 2, and taken substantially along line 3—3 of Fig. 2;

Fig. 4 is a diagrammatic cross section similar to Fig. 2 illustrating an alternative form of refrigerating chamber;

Fig. 5 is a diagrammatic longitudinal section of the chamber of Fig. 4, and taken substantially along line 5—5 of Fig. 4;

Fig. 6 is a fragmentary layout alternative to the layout of Fig. 1; and,

Fig. 7 is another alternative fragmentary layout.

Similar reference characters indicate corresponding parts throughout the several views of the drawing.

A principal objection to many of the refrigerating units of air conditioning systems in use today

is that they require a circulating secondary refrigerant, that is to say, a circulating liquid which, in a chilled condition, absorbs heat from the air being conditioned, and delivers up said heat to a heat-absorbing or refrigerating unit 5 where it is cooled and then recirculated. Such a system for example has been used with a heat-absorbing or refrigerating unit employing solid carbon dioxide as the heat-absorbing or refrigerating material. However, such a conditioning 10 system is disadvantageous under many circumstances, such as for example, in moving vehicles such as railroad cars, buses, trucks and passenger automobiles, because in the event of a wreck, the secondary refrigerant liquid is frequently released 15 from the system into the surroundings, rendering the equipment inoperative until it is replaced. This liquid frequently is either poisonous or at least, unpleasant. Even without wrecks, the leaks that normally occur in the liquid circuit in 20 the course of time permit the escape of this secondary refrigerant, and therefore its use is objectionable.

The present invention provides an air conditioning system wherein dry ice is used as the 25 heat-absorbing medium but wherein no secondary refrigerant is employed.

Fig. 1 is a diagrammatic view showing the several parts of an air conditioning system employing the present invention. Numeral 1 indicates 30 an air blower or fan which has an air inlet 2 and a discharge outlet 3. The blower or fan 1 may be of any type customarily used for this purpose. The outlet 3 delivers the air under suitable velocity and pressure to a tunnel indicated generally 35 by numeral 4 and which comprises a plurality of sections. The air first passes through section 5, which is a heating unit. This unit may be of any of the various types customarily used. For example, it may be a steam heating unit, in which event steam is admitted through an inlet 6 and discharged through an outlet 7. The heating unit 5 is ordinarily used only when the ambient air is too cold, and hence it is not ordinarily employed when the ambient air is too hot and the 40 present invention is used for chilling the air.

The next section in the tunnel 4 is indicated by numeral 8 and comprises a mixing unit. This merely comprises a length of conduit with baffles 9 therein so that the air is forced to travel 50 through a tortuous path and hence becomes uniformly mixed, for example, if the heating unit 5 is being used.

From the mixing unit 8 of the tunnel 4, the air passes to a cooling unit 10, with which the pres- 55

ent invention is particularly concerned. The cooling unit 10 comprises a heat exchanger of customary construction for two gaseous media. From the cooling unit 10, the air passes to individual conduits 11 which deliver it to the region to be conditioned.

The cooling unit 10 has an inlet 12 and an outlet 13. The inlet 12 is fed, by a conduit 14, with chilled carbon dioxide gas which is produced in a chamber 15. The construction of this chamber 15 is one of the particular features of this present invention and will be described in detail hereinafter. For present purposes, it is sufficient to state that the chamber 15 contains solid carbon dioxide or dry ice, and is provided with means for permitting the circulation of carbon dioxide gas therethrough.

The outlet 13 of the cooling unit 10 delivers into a conduit 16 which in turn delivers into a blower 20 or pump 37 which discharges through a conduit 38 to the chamber 15.

There is thus provided a continuous recirculation of carbon dioxide gas from the chamber 15 through the conduit 14 to the cooling unit 10, thence through the conduit 16 to the circulating blower 37 and through the conduit 38 back to the chamber 15. The circulated carbon dioxide gas is generated by the constant evaporation of the solid carbon dioxide in the chamber 15. Inasmuch as the solid carbon dioxide is constantly evaporating, this would mean, were no appropriate preventative steps taken, that the amount of carbon dioxide gas in the system would constantly be increasing. In order to maintain a constant volume of carbon dioxide gas in the circulating system at the desired pressure, a discharge line 17 branching from the conduit 16 is provided. The discharge line 17 has a pressure relief or regulator valve 18 therein. The regulator valve 18 is set to a predetermined pressure, say two pounds; and it automatically operates to discharge carbon dioxide gas whenever the pressure in the circuit rises above said two pounds. The value given, two pounds, is of course by way of example only, as any suitable pressure can be used at the operator's convenience.

Just ahead of the point where the conduit 14 connects to the inlet 12, there is provided a thermostatic regulator valve 19, which is controlled by a thermostat 20 positioned in the region for which the air is being conditioned. The regulator valve 19, when the temperature of the region rises too high, opens to allow a slow flow of cold carbon dioxide gas to the cooling unit 10 and hence to reduce the temperature of the air flowing to said region. Conversely, when said region becomes too cool, the thermostatic valve 19 operates the regulating valve 19 to diminish or cut off the flow of carbon dioxide gas to the cooling unit 10, and hence the air flowing through the unit is then not so greatly chilled.

All conduits are preferably heat-insulated. When the regulator valve 19 is closed there is a tendency for the carbon dioxide gas in the conduit 14 to build up an undesirably high pressure because of the pressure produced by the blower 37, provided the blower is of a positive displacement type. In order to prevent such accumulating pressure, a by-pass line 21 is provided from the conduit 14 to the conduit 16. It is connected into the conduit 14 ahead of the regulator valve 19. In the conduit 21 there is provided a pressure regulating or release valve 22. This valve 22 opens upon the exceeding of a predetermined

pressure, say two pounds, in the conduit 14 and permits the carbon dioxide gas to flow directly from the conduit 14 to the conduit 16, thus bypassing the cooling unit 10.

The advantages of the system as thus provided are numerous. The total heat-absorbing capacity of the solid carbon dioxide in the chamber 15 is utilized, without substantial waste, to absorb the heat from the air in the tunnel 4. This is true because the heat absorbing medium in the cooling unit 10 is carbon dioxide gas which is promptly recirculated to the chamber 15, where it delivers up the heat it has absorbed to the solid carbon dioxide and in so doing, not only vaporizes more solid carbon dioxide, but also becomes chilled itself. The carbon dioxide gas in the line 14 is thus thoroughly chilled. It comprises both recirculated gas from the lines 16 and 38, and fresh gas generated by evaporation of solid carbon dioxide in the chamber 15. In order to keep a regulated volume, and hence a regulated pressure of carbon dioxide gas in the system, the relief valve 18 functions to discharge a necessary amount of carbon dioxide from the circuit. However, the discharged carbon dioxide is not in its chilled condition, but in the warmed condition as a result of the absorption of heat from the air being conditioned.

If the thermostat 20 so functions as to close the regulating valve 19, then cold carbon dioxide gas passes from the conduit 14 through the by-pass conduit 21 to the conduits 16 and 38, and thence back to the cooling chamber 15. Inasmuch as no heat has been absorbed in this flow, no heat is delivered up to the solid carbon dioxide in the chamber 15, and hence further evaporation of the solid carbon dioxide in the chamber does not take place to any substantial extent. Hence, it will be seen that when the valve 19 is closed (indicating that no cooling is required in the unit 10), substantially no solid carbon dioxide is being consumed, and the solid carbon dioxide is being saved until conditions require that its heat-absorbing capacities be utilized.

The automatic manner in which the cooling circuit functions is one of the principal advantages of the invention. The only attention required is that a suitable quantity of solid carbon dioxide be maintained in the chamber 15 at all times.

The controlling features of the invention may likewise be obtained by the systems shown in Figures 6 and 7, among others. The system of Fig. 6, for example, differs from the Fig. 1 system in that the by-pass line 21 and regulator valve 22 are omitted, the blower 37 being of a fan type. A characteristic of such a blower is that it will not build up a pressure in excess of a predetermined value. Hence, when the thermostatic valve 19 closes, the pressure in line 14 builds up only slightly, and thereafter all circulation ceases, conserving the heat-absorbing capacity of the refrigerant.

In Fig. 7 a different system is shown wherein the thermostat 20, instead of controlling a valve, directly controls the operation of the blower 37, which may now be of either a positive displacement or a pump type. For example, when the ambient temperature drops too low, the thermostat 20 shuts off the blower 37, and circulation ceases, thus effecting the desired conservation.

As has been indicated hereinbefore, the construction of the chamber 15 is one of the principal features of the present invention. Figures 1 and 3 illustrate one form of the chamber, and

Figures 4 and 5 illustrate another form of the chamber. Referring now more particularly to Figs. 2 and 3, it will be seen that the chamber 15 comprises a rectangular box 23 formed of a good heat-insulating material, such as concentric metal boxes with a cork filler. The top 24 of the box 23 is illustrated as being removable for the purpose of filling the box 23, but it will be understood that any other section of the box 23 may be made removable for this purpose if desired. The box 23 is provided with a false bottom 25 which is perforated at frequent intervals as indicated at numeral 26. The false bottom provides a passage 27 of rectangular shape at the bottom of the box. An inlet opening 28 is provided at one end of the box for connection of the passage 27 to the conduit 38, while an outlet opening 29 at the other end of the box connects the passage 27 to the conduit 14. Extending downwardly from the false bottom 25 but terminating short of the bottom of the box 23, are a number of fins 30. The fins 30 as well as the false bottom 25 of the box 23, are usually made of metal so that they have a high heat conductivity. A partition 31 is provided at the outlet end of the box 23, extending entirely across said box from the false bottom 25 upwardly almost to the top of the box. The partition 31 provides a passage 32 which communicates with the passage 27 at the outlet port 29.

In operation, commercial rectangular blocks of solid carbon dioxide, indicated by numeral 33, are placed in the box 23, resting upon the false bottom 25. Relatively heated carbon dioxide gas enters the box through the inlet opening 28 and passes along the passage 27. The carbon dioxide gas delivers up its heat to fins 30 and the false bottom 25, which are kept cold by their contact with the solid carbon dioxide. The absorbing of the heat so delivered causes the solid carbon dioxide to vaporize, and the gaseous carbon dioxide thereby generated passes out through the perforations 26 to join the flow of carbon dioxide gas in the passage 27. Other carbon dioxide gas generated from the solid carbon dioxide blocks passes downwardly from the top of the box through the passage 32 to join the flow of carbon dioxide gas at the outlet 29. The carbon dioxide gas flowing out at the outlet 29 accordingly comprises fresh, cold carbon dioxide gas generated from the carbon dioxide, and cooled carbon dioxide gas which entered at the inlet 28.

Because the relatively heated carbon dioxide gas entering at the inlet 28 delivers up its heat to substantially only one surface of a solid carbon dioxide block 33, namely the surface in contact with the false bottom 25, substantially all evaporation of said solid carbon dioxide block 33 occurs at said surface. Hence, as operations continue, the block 33 evaporates in a uniform manner and remains in contact with the false bottom 25 over a substantially constant area. This is an advantageous provision as it means that the heat-absorbing capacity of the carbon dioxide is substantially constant in the box 23 as long as there is any solid carbon dioxide present, and hence the cooling effect is uniform throughout a cycle of operation.

If the heated carbon dioxide gas were admitted to the chamber 15 in such manner that it contacted the solid carbon dioxide blocks 33 indiscriminately, or over substantially the entire surface thereof, the blocks 33 would evaporate substantially uniformly over their entire surfaces, and as they evaporated, their surface area would

constantly decrease. This decreasing surface area would mean that the cooling effect on the incoming relatively heated carbon dioxide gas would constantly diminish, until such a time as substantially all of the solid carbon dioxide was used up, when the cooling effect would be negligible. However, by use of the chamber of the present invention, the evaporation of the solid carbon dioxide, as has been explained, is maintained almost entirely at one surface, and provision has been made for keeping said surface at substantially a constant area, so that a uniform cooling effect is obtained even as the quantity of solid carbon dioxide in the box 23 becomes less and less.

Figures 4 and 5 show a modified form of box 23 wherein the area of the surface provided for cooling the relatively heated carbon dioxide gas is increased, and hence the cooling capacity of the box is increased without sacrificing any of the advantages above indicated. Instead of the flat false bottom 25 of the embodiment of Figures 2 and 3, this embodiment has a trough-shaped false bottom 34, which is perforated and carries fins 30 as in the prior embodiment. The surface area of the trough-shaped bottom 34, it will be understood, is considerably greater than the surface area of the flat false bottom of the prior embodiment. In using this embodiment, solid carbon dioxide blocks 33 of rectangular shape are still used, but the block 33 at the bottom soon conforms to the triangular shape of the trough, under its own weight. This means that when fresh, rectangular blocks of carbon dioxide are placed in an empty box 23, the full cooling effect will not be realized until the shape of the bottom-most block 33 conforms to the shape of the trough 34. However, this takes but a relatively short time and after the shaping has been accomplished the first time, no further delay is encountered if fresh rectangular blocks are placed in the box 23 sufficiently often that sufficient solid carbon dioxide is always present to fill the trough 34.

The principle underlying both embodiments of the chamber 15 as herein described will readily be seen to comprise the provision of means whereby the solid carbon dioxide is evaporated over a predetermined constant surface area only.

It will be apparent that the present invention is useful not only with carbon dioxide, but also with any other substance which is readily obtained in solid form and which evaporates at proper temperatures to a vapor without going through an intermediate liquid phase.

The construction of the chamber 15, it is to be noted, may also be advantageously employed for the direct cooling of air, for example, with blocks of water ice, because the water ice will melt and cool the air current in substantially the same uniform-area manner as heretofore described in connection with the solid carbon dioxide.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawing shall be interpreted as illustrative and not in a limiting sense.

I claim:

1. In an air conditioning system, a cooling unit, and a chamber, said chamber containing a substance in its solid phase which passes, upon the

- absorption of heat, directly to its gaseous phase, conduit means connecting the outlet of said chamber to the inlet of said cooling unit, conduit means connecting the outlet of said unit to the inlet of said chamber, whereby said substance in its gaseous phase, circulates from said chamber to said cooling unit and back to said chamber, and a by-pass conduit around said cooling unit, said by-pass conduit having a pressure regulating valve therein, whereby gas is by-passed through said by-pass conduit when the pressure of gas in said conduit leading from said chamber to said cooling unit increases above a predetermined amount.
2. In an air conditioning system, a cooling unit, and a chamber, said chamber containing a substance in its solid phase which passes, upon the absorption of heat, directly to its gaseous phase, conduit means connecting the outlet of said chamber to the inlet of said cooling unit, conduit means connecting the outlet of said unit to the inlet of said chamber, whereby said substance in its gaseous phase circulates from said chamber to said cooling unit and back to said chamber, means for regulating the amount of gas passing from the chamber to said cooling unit in accordance with the temperature of the region to be conditioned, and a by-pass conduit around said cooling unit, said by-pass conduit having a pressure regulating valve therein, whereby gas is by-passed through said by-pass conduit when the pressure of gas in said conduit leading from said chamber to said cooling unit increases above a predetermined amount.
3. In an air conditioning system, a cooling unit, and a chamber, said chamber containing a substance in its solid phase which passes, upon the absorption of heat, directly to its gaseous phase, conduit means connecting the outlet of said chamber

ber to the inlet of said cooling unit, conduit means connecting the outlet of said unit to the inlet of said chamber, whereby said substance in its gaseous phase circulates from said chamber to said cooling unit and back to said chamber, means for regulating the amount of gas passing from the chamber to said cooling unit in accordance with the temperature of the region to be conditioned, a by-pass conduit around said cooling unit, said by-pass conduit having a pressure regulating valve therein, whereby gas is by-passed through said by-pass conduit when the pressure of gas in said conduit leading from said chamber to said cooling unit increases above a predetermined amount, and pressure-regulated discharge means in the conduit connecting said cooling unit and said chamber.

4. The system as set forth in claim 1 in which the substance comprises carbon dioxide.

5. The system as set forth in claim 2 in which the substance comprises carbon dioxide.

6. The system as set forth in claim 3 in which the substance comprises carbon dioxide.

7. A chamber for the purposes described comprising a heat-insulating box, said box having a false bottom therein, means for admitting gas at one end of said box under said false bottom, and for discharging gas at the other end of said box under said false bottom, the space above said false bottom being adapted to receive and store solid refrigerating material, and a passage at one end of said box extending upwardly from beneath said false bottom substantially to the top of said box, and being open at the top of said box, thereby to conduct gases from the space above said false bottom into the space below said false bottom.

JESSE A. GUYER.
